CLAIM

I claim the ornamental design for a basketball hoop lock, as shown and described.

DESCRIPTION

FIG. 1 is perspective of a basketball hoop lock showing my new invention in its open state;

FIG. 2 is a perspective of the basketball hoop lock of FIG. 1 shown in its closed state;

FIG. 3 is a front elevational view of the basketball hoop lock of FIG. 2;

FIG. 4 is a left side elevational view of the basketball hoop lock of FIG. 2;

FIG. 5 is a rear elevational view of the basketball hoop lock of FIG. 2;

FIG. 6 is a right side elevational view of the basketball hoop lock of FIG. 2;

FIG. 7 is a top plan view of the basketball hoop lock of FIG. 2; and,

FIG. 8 is a bottom plan view of the basketball hoop lock of FIG. 2.

The broken line environmental showing is for illustrative purposes only and forms no part of the claimed design.
